UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,269,993.

Specification of Letters Patent. Patented June 18, 1918.

Application filed October 1, 1912. Serial No. 723,268.

To all whom it may concern:

Be it known that I, WALTER WRIGHT, a citizen of the United States, residing in New York city, in the county of New York and 5 State of New York, have invented certain new and useful Improvements in Combined Type-Writing and Computing Machines, of which the following is a specification.

This invention relates to combined type-writing and computing machines, particularly those which are adapted to do computing in a number of different columns. This application refers to matter covered in several prior applications, among which is application No. 543,603, filed jointly by Gustave O. Degener and myself, February 12, 1910, and an application of Gustave O. Degener, No. 754,709, filed March 17, 1913; also my Patent No. 1,162,730, dated November 20, 1915. To the overlapping subject-matter of such applications and the present application, I make no claim *per se*, and only intend to claim in this application, such combinative relations as the new parts disclosed 25 in the present application over such above-mentioned applications, combine with the old features to perform in the aggregate new results.

As herein illustrated, this invention is applied to a combined typewriting and computing machine of the Underwood-Wright type, in which the carriage of the typewriter carries a platen on which the writing sheet is placed. This platen, as in an ordinary typewriter, has a letter-feeding motion and is arranged in said motion to control the *seriatim* connection between the numeral keys of the typewriter and the computing wheels of the computing mechanism proper.

For this purpose in said combined machine the computing wheels are mounted in a totalizer, and the master-wheel is connected to said carriage to be moved thereby, so as to engage the computing wheels in said totalizer *seriatim*. For computing in several columns tabulator stops may be provided which are arranged to automatically establish and let go said connection between the typewriter carriage and the master-wheel in the totalizer. This enables writing done on a work sheet in several different columns to be computed in one totalizer as though it were in a single column. This connection between the tabulator stops and the master-wheel may be made by a hook adjacent the

typewriter carriage, and every time the typewriter carriage carries a stop past said hook, it automatically catches the hook by means of the stop and thereby causes said master-wheel to be moved by the hook for 60 predetermined distances. A cam on the hook may be arranged to ride under a stud and force said hook free of said stop when beyond any computing zone.

The present invention is illustrated as applied to such a computing machine having a plurality of totalizers separately connectible to the numeral keys. For the purpose of varying the nature of the connections between the numeral keys and the computing wheels, the stops may be provided with projections, which, in the travel of the typewriter carriage, are arranged to shift a clutch or clutches in the gearing between said wheels and said keys. Each of these 75 clutches, for example, in one position may cause the master-wheel to rotate the computing wheels so that they add, in another position may rotate them so that they subtract, or the clutch may be absolutely neutral, as 80 the case may require. The stops may control each clutch separately by means of cam arms hung in the typewriter frame, which arms are drawn by springs to engage said stops as the stops travel with the typewriter carriage. 85

In order to avoid noise and wear of the parts, and to reduce the amount of shifting of said clutches, the operation of a tabulating key may also always shift any clutch into one selected position and hold it there 90 until said key is released. As most computing is in the form of addition, it is convenient to cause a clutch to be always held at its adding position, unless moved to some other position by the controlling stops. The 95 clutch-controlling arms preferably are in their outermost position when they cause the mechanism to add, and may be arranged to be moved to said outermost position where they are practically free from the stops by 100 means of a universal member, which is swung at every operation of any tabulator key. In this way, if the typewriter carriage is caused to travel over several columns without computing, unnecessary shifting of 105 a clutch is avoided.

Other features and advantages will hereinafter appear.

In the accompanying drawings,
Figure 1 is a diagrammatic side view of 110

an Underwood-Wright typewriting and computing machine, showing my invention applied thereto.

Fig. 2 is a perspective view of some principal parts of the computing mechanism.

Fig. 3 is a section through a totalizer.

Figs. 4 and 5 are respectively plan and perspective views of the connection between the tabulator stops and the totalizer.

10 Fig. 6 is a detail of the same.

Fig. 7 is a perspective view showing some parts especially connected with the present invention.

Fig. 8 is a rear view of the same.

15 Fig. 9 shows various combinations of automatic stop-controls.

Numerical keys 1 and letter keys 2 of the typewriter depress levers 3 to cause bell cranks 4 to swing type bars 5 upwardly and 20 rearwardly against the platen 6, so that type 7 will write on a work sheet thereon. Said platen is mounted in a carriage 8, traveling on rails 9 and 10, and said carriage is drawn forward in letter-feeding direction 25 by means of a spring barrel 11, and is controlled in said letter-feed by means of an escapement wheel 12, carrying a ratchet wheel 13 which works in a rack 14 connected to the carriage. Said escapement wheel is 30 controlled by means of dogs 15 and 16, which dogs are operated by an extension 17 of a universal member 18, which universal member is operated by heels 19 on the type bars as they rise toward the platen.

35 Each numerical key as it is depressed is arranged to operate the computing mechanism escapement, which is in the nature of an indexing or valuating mechanism acting to cause the numbers written to be carried into the computing wheels. For this purpose each numerical key is engaged by a link 20 (Fig. 2) depending from a bell crank 21, which bell crank is joined by a link 22 to the computing escapement proper.

45 When the key 1 is depressed, it draws link 22, so as to cause the lever 23 to thrust forward a digit determining jack 24 and projects a pin 25 from the computing, escapement or valuating or index wheel 26. At the same 50 time a universal disk 27 is drawn backward at the head of said link 22, so that the lever 28 rocks the link 29 controlling a secondary escapement, and said secondary escapement comprises a star-wheel 30, which has been 55 holding the escapement wheel 26 against revolving by means of a pin 25 thereon, which had been previously projected.

The escapement wheel 26 constantly tends to be turned by a motor 31 through a friction slip clutch, not shown, bevel gears 32, 33, and a shaft 34, which shaft has fast to it a bevel gear 35, meshing with a bevel gear 36; and said bevel gear 36 is fast on a shaft carrying a gear wheel 37, which in 65 turn meshes with a gear wheel 38 fixed to

the escapement wheel 26. As the link 29 is moved forward at the depression of a numerical key, it allows the engaging tooth of a secondary escapement wheel 39 fast on the shaft of star-wheel 30 to escape past 70 a dog 40, so that it strikes a dog 41, and on the return stroke of said numerical key, said tooth 39 escapes from the dog 41 and allows the escapement wheel 26 to carry around its pin 25 which has been bearing against the 75 star-wheel 30, so that said escapement wheel 26 can turn until the pin 25, which has just been projected by the jack 24, strikes the succeeding tooth of the star wheel 30. Said escapement wheel 26 is 80 then held against revolution by means of a second tooth 39 of the secondary escapement wheel, which has been brought around to bear against the dog 40 when the pin 25 strikes the tooth of the star wheel 30. 85

As the motor 31 turns said escapement wheel 26, it turns the bevel gear 42, which is constantly in mesh with the bevel gear 36 and will, through shaft 43, turn the vertical shaft 44 by means of bevel gears 45 90 and 46, and in so doing will cause the number then written and computed or indexed, or valuated, by the escapement wheel 26 to be carried into a totalizer 47. The projected pin 25, which has been previously engaging the star-wheel 30, is returned by a cam wiper, not shown herein, after it passes said wheel.

In the machine herein shown, there are two totalizers 47, which may be identical 100 and the description of one will answer for both. In each of said totalizers 47 there is a series of computing wheels 48 (Fig. 3), which are arranged to be engaged *seriatim* by a master-wheel 49 lying within said computing wheels and arranged to be carried back and forth within said wheels to engage them *seriatim* in a manner presently to be described.

When engaged with any computing 110 wheel 48, said master-wheel is arranged to be turned by means of a square shaft 50 on which it is slidably mounted, and said shaft extends through the frame of the machine at 51 where there is fast on it a bevel gear 115 52, meshes with bevel gears 53 and 54 on shaft 44, and may be clutched to be turned by one of them in a manner to be herein-after described. Said master-wheel, as will be seen, comprises a hub 55, which is freely 120 revolvable in a sleeve 56, which sleeve, however, moves said master-wheel successively into engagement with the various computing wheels. For so moving it, there is provided on the carriage 8 of the typewriter 125 a rack bar 57 carrying settable lugs 58, which lugs are arranged to successively engage, as seen in Fig. 5, a hook 59 comprising a notch 60 in which said lugs rest when moving it.

Said hook 59 is formed as the end of a sliding rod 61 in the casing 62 fast on the typewriting machine. Projecting downwardly from said rod through a slot 63 in the casing, is a pin 64 engaging one arm of a lever 65, which is pivoted between its ends at 66, of which lever the two front arms 67 and 68 engage computing carriages 69, of which carriages the sleeves 56 controlling the *seriatim* engagement of the master-wheels form a part. This lever 65, as seen from the rear and above in Fig. 4, is normally drawn to the right by means of a spring 70 anchored in the frame of the machine, and in such position holds the master-wheels 49 in a position to engage the highest wheel in each of said totalizers. From such position it is drawn by means of the hook 59, as above described, so that at each letter-space movement of the typewriter it moves the master-wheels to engage step-by-step with the various computing wheels.

When said hook 59 has drawn the master-wheels so that they engage with the units computing wheels, the cam end 71 of the hook is caused to release said hook from the lug 58 by striking a pin 72 fast on the frame of the machine, under which pin said hook is drawn until it swings downward clear of the stop 58, and then is drawn backward to the highest computing wheel by the spring 70. Said hook 59 is held upward in position where the next lug 58 will strike it by means of a spring 73 bearing against a screw 74 entered in a socket in the frame of the typewriting machine.

The lever 65 is slotted at each end where it engages the pins 64 and 75, the latter pins being the means by which it is connected to the carriages 69, which causes step-by-step movement of the master-wheels. Each computing carriage 69 comprises, in addition to the sleeve 56, a sleeve 76, which embraces a rod 77 fast on the frame of the typewriting machine and carrying in its opposite end a cross rod 78, which cross rod also supports the outer end of a rod 79, said rod 79 embraced by the plate 80 forming the union between the sleeves 56 and 76 of the master-wheel carriage.

When returning the carriage 8 to begin a new line of writing, if the hook 59 is in engagement with one of the lugs 58, it is carried to the left in Fig. 5 until the cam edge 81 thereon strikes a stud or roller 82, which may be pivoted on a screw 83 threaded into the top of the boss 84 on which the screw 83 is mounted, and by means of said roller, the hook is cammed downwardly and released from the lug 58. The spring 73 immediately raises the hook, and the lugs 58 in succession ride freely over a bevel or point 85 on the tip of the hook, the last lug in the series being caught and held by the hook

when the carriage begins to run in letter-feeding direction.

The totalizer 47 comprises a casing 86 (Fig. 3) through a sight opening 87 in which numerals of the dial wheels 88 may be read. Each dial wheel is constantly in mesh with an external gear 89 of its computing wheel 48, and said computing wheel carries internal teeth 90, as seen in Fig. 3, arranged to be engaged by the teeth 91 of the master-wheel 49. Each computing wheel also is constantly in mesh with a carry-over wheel 92 comprising three different forms of teeth. Of these forms of teeth, one set 93 constantly meshes with the gear 89 of the computing wheel 48, so as to turn said wheel when the carry-over wheel is turned one unit's space by the computing wheel next lower in denomination. Each computing wheel also comprises a special tooth, not shown herein, which is arranged to strike a tooth 94 on the carry-over wheel geared to the computing wheel next higher in denomination, and give that carry-over wheel a slight turn when the zero of the computing wheel turns to the sight opening 87. In giving said wheel this slight turn, it moves it so that teeth 95 of the third form on said computing wheel engage resilient roll 96, which is power-driven, and said roll completes the turning of the carry-over wheel its one unit space. Said resilient roll 96 is driven by a gear wheel 97 meshing with a gear fast on it, which gear wheel 97 in turn is driven by a pinion 98 fast on its shaft, and said pinion is driven by a gear wheel 99 fast on a shaft 100, which is geared to the motor through a bevel gear 101, as will be presently described.

It has been stated that the wheels in the totalizer may be turned either to add or subtract, and for this purpose on the shaft 44 which drives said wheels, as described above, there is formed a clutch 102 for each totalizer comprising a member 103 slidably splined on said shaft 44 and arranged to lock internally with either the upper bevel gears 54 or the lower bevel gears 53, which bevel gears turn loose on said shaft. The clutch member 103, for this purpose, may be shifted by means of a handle 104 pivoted at 105, and on an extension of said handle is formed a series of notches 106 arranged to engage a detent 107 and hold said clutch member in whatever position it may be placed. When a handle 104 and its clutch member 103 is in its uppermost position as shown in connection with the top totalizer in Fig. 1, the computing wheels thereof will be rotated for addition; while if the handle and clutch is in an intermediate position, the computing wheels of the associated totalizer will be unaffected by the rotation of the shaft 44; but if the handle 104 is in its lowermost position, as in connection with the bottom totalizer in

Fig. 1, then the shaft 44 will drive the computing wheels *seriatim*, through the aid of the master wheel 49, in a subtracting manner.

5 For enabling the power-driven resilient roll 96 of the carry-over mechanism to be reversed simultaneously with the reversal of the master-wheels, a set of clutches is provided for the carry-over mechanism similar 10 to those provided for the master-wheel shafts comprising shiftable members 108, which are operated by extensions of the handles 104, extending beyond the pivots 105, so as to shift said members 108 simultaneously 15 with the shifting of the members 103 for the master-wheels. Said members 108 are slidably splined on a shaft 109, and may occupy an intermediate neutral position or alternatively clutch either one of a pair of 20 oppositely-facing bevel gears for each totalizer, similar to the gears 53, 54, in driven relation with the shaft 109, which gears mesh with the gears 100 to drive the rubber tens-carrying rollers 96 alternatively in opposite 25 directions to correspond with the adding or subtracting rotation of the associated master wheels. The shaft 109 is driven from the motor 31 by means of a bevel gear 110 fast on said shaft 109, a bevel gear 111 meshing therewith, which bevel gear is fast on a shaft 112 carrying a bevel gear 113 meshing with a bevel gear 114 fast on shaft 34.

The lugs 58, which have been above described as connecting the master-wheels to the typewriter carriage so that they have a similar step-by-step movement, are preferably formed as extensions of tabulating stops 115 also mounted on the rack bar 57. Said tabulating stops are arranged to co-operate with key-operated plunger stops 116 of the usual Underwood type, operated from keys 117 at the front of the keyboard, mounted on levers 118, pivoted at 119, which levers carry said plunger stops at their rear ends 120. Each of said tabulator keys is arranged, when it is operated, to release said typewriter carriage 8 from the escapement mechanism in the usual manner. The connections for accomplishing said release 50 include a universal bar 121 operated by heels 122 on the stop plungers 116, and said universal bar is fast on a rock shaft 123 carrying a rock arm 124, which through a link 125 draws down the rear end of a lever 55 126, so as to swing the front end thereof upward and cause an idle wheel 127 thereon to lift the typewriter carriage rack 14 out of the ratchet wheel 13. When the carriage is thus released from its escapement wheel 60 12, it is drawn forward in letter-feeding direction until the stop plunger 116 arrests it by intercepting a carriage stop 115. Said plunger stops 116 form a decimal tabulator inclosed in a casing 128.

65 The carriage stops 115, in addition to the

lugs or extensions 58, also include projections or levels 129, 130 and 131 (Fig. 9). Said projections are of varying depth and are arranged to automatically shift the the clutches 102, 108, which control the turning of the computing wheels by means of the numeral keys and the rotation of the carry-over mechanism, thus relieving the operator of the necessity of manually shifting the handles 104. For this purpose there is journaled on the casing 128 a shaft 132 carrying a rock arm 133, which rock arm is arranged to co-operate with the upper end of one of the stops 115. When said rock arm 133 rocks to its innermost position corresponding to a subtracting projection or level 130 at the upper portion of a carriage stop 115, as seen in Fig. 1, it rocks an arm 134 fast on said shaft 132, so as to move a forwardly extending link 135 pivoted on said rock arm 133 to swing a bell crank 136 rearwardly, so that the arm 137 thereof, which is pivoted by a pin-and-slot connection 138 to an extension of the lower handle 104 for the lower totalizer, will shift said handle into its downward position at the forward end and cause said clutch to connect the master-wheel to subtract. In a similar way an outer adding projection or level 129 of the lower end of a stop 115 is arranged to swing arm 139 fast on a sleeve 140 on said shaft 132, and thereby swing arm 141 fast on said sleeve to draw an upper link 142, so as to cause its bell crank 143 to swing its extension 144 to swing the upper handle 104 for the top totalizer 100 upwardly at its forward end and thus cause said totalizer to add.

It will be observed that the rock arms 134 and 141 extend in opposite directions, and to offset this, the bell cranks 136 and 143 are set to work in opposite directions, so that identical projections or levels of the stops 115 will have identical effect on both rock arm 133 and rock arm 139. Each of said rock arms 133 and 139 is drawn by a spring 145 in a forward direction constantly tending to move it to cause the computing mechanism to subtract.

In order to enable the typewriter carriage to feed past the flat faces 146 and 147 of rock arms 133 and 139 respectively, the ends thereof are beveled as at 148 to form cam surfaces which will force said arms outwardly when the stops strike them. Each flat face 146, 147 is of the width of the computing column or zone so as to hold the clutches 53 in position throughout the column or zone. Each of the rock arms 133 and 139 is formed where it is fast onto its shaft or sleeve respectively, comparatively narrow, so that the two portions thereof where fast to their shaft and sleeve will not take up more than the column over which they are arranged to affect the computing mechanism. The rock arm 139 is formed 130

with a narrow portion 149 and then at the top is extended broadly so that the edge 147 is of length equal to a computing column. The rock arm 133 is formed with a 5 narrow portion 150, which then extends to the right and then upwardly at 151, and then to the left at 152, so that the edge 146 will be of precisely the same length as edge 147, and precisely above it. In this way the 10 two rock arms 133 and 139 swing perfectly clear of each other, and operate on the same column. The rock arm 133 in its narrow portion is bent outwardly at 153, so that the narrower portions 149 and 150 near their 15 tops will lie in the same plane when not engaging stops 115.

Whenever a tabulating key 117 is depressed, these rock arms 133 and 139 are automatically swung outwardly so as to be 20 practically clear of the stops 115. For this purpose, the rock shaft 123, which operates the carriage release mechanism, carries also a rock arm 154 fast thereon, which strikes the tail of a lever 155, the upper end of 25 which has a broad-edge 156, and when the rock shaft 123 is swung by the depression of any tabulating key, the rock arm 154 will swing the flat surface of the lever 156 against the rock arms 133 and 139 and swing 30 them outwardly. Owing to a little lost motion in the clutches, these rock arms 133 and 139 can be swung completely clear of the 35 stops 115, and thus the carriage may travel unimpeded by the edges 146 and 147 of said rock arms.

The stops 115 may include any desired combination of adding, subtracting and neutral positions, such as are shown in Fig. 9. The rock arms 133 and 139 are locked to 40 their carrying members by means of set screws 157 and 158, so that they may be adjusted thereon, and the lever 155 is pivoted as a sleeve outside of the sleeve 140 and may be held against the frame 128 by 45 means of a pin 159 fast on the sleeve 140.

Variations may be resorted to within the scope of the invention; and portions of the improvements may be used without others.

Having thus described my invention, I 50 claim:

1. In a typewriting machine, the combination with numeral keys and a plurality of gangs of computing wheels, of a typewriter carriage, a tabulating mechanism comprising stops for positioning said carriage, keys for operating said tabulating mechanism, lugs carried by said stops for separately connecting said numeral keys to said wheels, and means for disabling said connections 55 when said tabulating keys are operated.

2. In a typewriting machine, the combination with numeral keys and computing wheels, of a typewriter carriage, a tabulating mechanism comprising a stop for positioning said carriage, a key for operating

said tabulating mechanism, a bar swung by a lug on said stop to automatically connect said numeral keys to control said wheels, and an arm moved by depression of a tabulating key to swing said bar clear of 70 said lug.

3. In a typewriting machine, the combination with numeral keys and computing wheels, of a typewriter carriage, a tabulating mechanism comprising a stop for positioning said carriage, keys for operating said tabulating mechanism, a bar swung by a lug on said stop to automatically connect said numeral keys to control said wheels, a universal bar moved by each tabulator key, and 80 an arm swung by said universal bar to move said bar clear of said lug.

4. In a typewriting machine, the combination with numeral keys and computing wheels, of a typewriter carriage, a tabulating device comprising keys for positioning said carriage, rack stops, cooperating stops operated by said tabulating keys, means operated by said rack stops for varying the 85 control of the connection between said wheels and said numeral keys, and means operated by said tabulating keys for maintaining said connection at a predetermined position while said tabulating keys are operated to cause said carriage to travel. 90

5. In a typewriting machine, the combination with a traveling carriage, numeral keys and computing wheels, of a tabulating mechanism for positioning said carriage, a plurality of denominational stops in said mechanism, a universal bar operated by said denominational stops, a series of rack stops, a bar operated by said rack stops for connecting said keys to control said wheels, and a lever swung by said universal bar to cause 100 said stop-operated bar to swing free of said stops. 105

6. In a typewriting machine, the combination with a traveling carriage, numeral keys and computing wheels, of a tabulating mechanism for positioning said carriage, a plurality of denominational stops in said mechanism, a clutch between said wheels and keys, a universal bar operated by said denominational stops, a series of rack stops, 110 a bar operated by said rack stops for controlling said clutch, and a lever swung by said universal bar to cause said stop-operated bar to swing free of said stops. 115

7. In a typewriting machine, the combination with a traveling carriage, numeral keys and computing wheels, of a tabulating mechanism for positioning said carriage, a plurality of denominational stops in said mechanism, a clutch between said wheels and keys, a pivoted arm for shifting the seizing member of said clutch, a series of rack stops, a cam bar adjacent said rack stops, a link connecting said cam bar to said pivoted arm to shift said clutch, a universal bar 120 125 130

operated by said denominational stops, and a lever swung by said universal bar to swing said cam bar clear of said stops.

8. In a typewriting machine, the combination with a traveling carriage, numeral keys and computing wheels, of a stop for said carriage, means for controlling the connection between said wheels and said keys by said stop, when the carriage is in any computing zone, tabulating keys, and means for breaking said control by the operation of a tabulating key during a change from one computing zone to another.

9. In a typewriting machine, the combination with a traveling carriage, numeral keys, and computing wheels, of a rack stop, a series of key-operated stops, means for controlling the connection between said wheels and keys by said rack stop, and means for breaking said control by the operation of a key-operated stop.

10. In a typewriting machine, the combination with numeral keys and a traveling carriage, of a plurality of gangs of computing wheels, stops on said traveling carriage, a master-wheel for each gang of computing wheels, lugs on a plurality of said stops to connect said master-wheels to said carriage, means to separately and variably control the connection of each master-wheel to the numeral keys by the appropriate ones of said lugs, a tabulating device comprising keys for coöperating with said stops, and means operated by each tabulating key for disconnecting said lugs from the means which they control.

11. In a typewriting machine, the combination with numeral keys and a traveling carriage, of a gang of computing wheels, a master-wheel for said gang, a rack bar, stops on said rack bar, key-operated denominational stops for positioning said carriage by coöperation with said rack stops, a cam bar operated by extensions on said rack stops, a clutch for said master-wheel, a rock shaft swung by said cam bar to shift said clutch, a link from said rock shaft to said clutch, and a universal bar swung by said key stops to swing said cam bar free from said extensions.

12. In a typewriting machine, the combination with numeral keys and a traveling carriage, of a plurality of gangs of computing wheels, stops on said traveling carriage, a master-wheel for each gang of computing wheels, extensions on said stops, a pair of separably operable cam bars, separately and variably moved by said extensions, a shaft to which one arm is fast, a sleeve on said shaft to which the other is fast, a series of key-operated denominational stops, a universal bar swung by said key stops and arranged to move said cam bars to inoperative position, and means for controlling said gangs from said sleeve and shaft.

13. In a typewriting machine, the combination with numeral keys and a traveling carriage, of a plurality of gangs of computing wheels, stops on said traveling carriage, a master-wheel for each gang of computing wheels, means for causing said master-wheels to have a simultaneous step-by-step motion relative to their gangs, means controlled by said stops for variably connecting said master-wheels to said keys, tabulating keys for positioning said carriage by said stops, and connections from said tabulating keys for making said master wheel control connections ineffective.

14. In a typewriting machine, the combination with numeral keys and a traveling carriage, of a plurality of gangs of computing wheels, a master wheel for each gang of computing wheels adapted to rotate them, a rack bar, a series of stops on said rack bar, key-operated denominational stops for positioning said carriage by coöperation with said rack bar stops, extensions on said rack stops, a rock arm carrying a cam bar arranged to be moved by one of said extensions, a rock shaft carrying said arm, a second rock arm carrying a second cam similarly moved by another of said extensions, a rock sleeve on said rock shaft, rock arms fast on said sleeve and shaft, a clutch for each gang of computing wheels, a link connecting each of said clutches to its one of said rock arms to enable that arm to shift its clutch, and a universal bar operated by said key stops for making said cams ineffective to shift said clutches.

15. In a typewriting machine, the combination with numeral keys and a traveling carriage, of a plurality of gangs of computing wheels, stops on said traveling carriage, a master-wheel for each gang of computing wheels, extensions on said stops, a pair of separably operable cam bars variably moved by various ones of said extensions, arms operated by said extensions, a shaft to which one arm is fast, a sleeve on said shaft to which the other is fast, means for controlling said gangs from said sleeve and shaft, a tabulating mechanism for positioning said carriage by said stops, and means operated by said tabulating mechanism for making said extensions ineffective.

16. In a typewriting machine, the combination with numeral keys and a traveling carriage, of gangs of computing wheels, a master-wheel for each gang, said carriage connected to produce a relative movement between said master-wheel and said gangs, a rack bar, stops on said rack bar, an extension on one of said stops, another different extension on one of said stops, a separate cam bar for each kind of extension, all of said cam bars covering the same travel of the carriage, supporting means upon which said cam bars shift, means controlled by said

cam bars for affecting said computing mechanism, and a tabulating mechanism for said carriage automatically making said cam bars ineffective.

5 17. In a typewriting machine, the combination with numeral keys and a traveling carriage, of gangs of computing wheels, a master-wheel for each gang, a rack bar, stops on said rack bar, an extension on one of 10 said stops, a different extension on one of said stops, a separate cam bar for each kind of extension, all said cam bars covering the same travel of the carriage, clutches for said master-wheels at one end of the machine, rock members connecting said cam bars to links at said end, means for shifting said clutches by said links, and a tabulating mechanism for said carriage automatically making said cam bars ineffective while the 15 tabulating mechanism is effective.

18. In a combined typewriting and computing machine, the combination with numeral keys and a traveling carriage, of a computing device, means controlled by said 20 traveling carriage for causing said computing device to add or subtract the numbers represented by the keys operated, a tabulating device, and means effective on the 25 operation of said tabulating device for holding said carriage controlled means in a position where said carriage will travel clear of it.

19. In a combined typewriting and computing machine, the combination with numeral keys and a traveling carriage, of a computing device, means whereby numbers represented by the keys operated are registered in said computing device, a reversing 30 device for causing said numbers registered to be either added or subtracted, tabulating keys for positioning said carriage, and means operated by said tabulating keys for holding said reversing device in a given position while the typewriter carriage travels.

40 20. In a combined typewriting and computing machine, the combination with numeral keys and a traveling carriage, of a computing device, means whereby numbers represented by the keys operated are registered in said computing device, a reversing 45 device for causing the numbers so registered to be added or subtracted, an arm operated by said traveling carriage to cause said reversing device to be shifted automatically to add or subtract, tabulating keys for positioning 50 said carriage, a universal bar operated by said tabulating keys, and an arm swung by said universal bar to move said carriage controlling arm to a position where 55 the carriage will travel without vibrating it.

60 21. In a combined typewriting and computing machine, the combination with numeral keys and a traveling carriage, of a computing device in which numbers are registered as written by said numeral keys, a

reversing device for causing the numbers so registered to be added or subtracted in said computing device, a rack bar for controlling the feed of said carriage, tabulating keys for freeing the carriage from said rack bar 70 to locate it, a universal bar operated by the tabulating keys for so releasing it, an arm moved by said traveling carriage to automatically shift said reversing device to add, subtract or be neutral, and an arm connected 75 to said universal bar for moving said carriage controlled arm to a position where the carriage may travel without operating it.

22. In a combined typewriting and computing machine, the combination with numeral keys, computing wheels and a traveling carriage, of a clutch for determining how said wheels shall turn under the influence of said keys, a lug on said carriage, an arm coöoperating with said lug and 80 connected to said clutch, tabulating keys for positioning said carriage, and means effective at the operation of any tabulating key to make said lug ineffective on said arm. 85

23. In a combined typewriting and computing machine, the combination with numeral keys, computing wheels, and a traveling carriage, of a clutch for determining how said wheels shall turn under the influence of said keys, a lug on said carriage, an arm for operating said lug and 90 connected to said clutch, tabulating keys for positioning said carriage, a tabulating-column stop rack bar on which said lug is settable, and means effective on the operation of any tabulating key to make said lug ineffective on said arm. 95

24. In a combined typewriting and computing machine, the combination with numeral keys, a plurality of sets of computing wheels and a traveling carriage, of a master wheel for each set of wheels for determining how the wheels of that set shall turn under the influence of said keys, a clutch for each set for determining how that master wheel shall turn its wheels, a lug on said carriage, an arm for each group of computing wheels connected to the clutch for said wheels and coöperating with said lug, tabulating keys for positioning said carriage, and means for making said lug ineffective on said arms whenever a tabulating key is operated. 110

25. In a combined typewriting and computing machine, the combination with numeral keys, a plurality of sets of computing wheels and a traveling carriage, of a master wheel for each set for determining how its wheels shall turn under the influence of said keys, a clutch for each set for determining how that master wheel shall turn its wheels, a lug on said carriage, an arm for each group of computing wheels connected to the clutch for said wheels and coöperating with said lug, tabulating keys 115 120 125 130

for positioning said carriage, extensions of said lug whereby it variably coöperates with each arm, and means for making said lug ineffective on said arms whenever a tabulating key is operated.

26. In a combined typewriting and computing machine, the combination with numeral keys, a plurality of sets of computing wheels and a traveling carriage, of a master wheel for each set for determining how its wheels shall turn under the influence of said keys, a clutch for each set for determining how that master wheel shall turn its wheels, a lug on said carriage, an arm for each group of computing wheels connected to the clutch for said wheels and coöperating with said lug, tabulating keys for positioning said carriage, means for making said lug ineffective on said arms whenever a tabulating key is operated, a spring normally holding each arm in effective position against said lug, and means effective at the operation of every tabulating key for tensioning said springs to make said lug ineffective on said arms.

27. The combination with computing wheels, of a master wheel for operating said computing wheels *servatim*, numeral keys for controlling the extents of rotation of said master wheel, a carriage traveling to determine different computing zones for said computing wheels and said master wheel, automatic controlling means for determining the connection of said keys to said wheels, tabulating mechanism for jumping said carriage from one computing zone to another, and silencing means for said automatic controlling means brought in play by said tabulating mechanism during the operation thereof.

28. The combination with computing wheels, of actuating mechanism for driving said computing wheels, numeral keys for controlling the extents of driving action of said actuating mechanism, a carriage traveling to determine different computing zones for said computing wheels and actuating mechanism, tabulating mechanism for jumping said carriage from one computing zone to another, controlling means operated from a part of said tabulating mechanism

for determining the connection between said keys and said computing wheels, and means brought into play by said tabulating mechanism during the action thereof, to limit the action of said controlling means during a tabulating movement of said carriage.

29. The combination with computing wheels, of actuating mechanism for driving said computing wheels, numeral keys for determining the extents of driving action of said actuating mechanism, a traveling carriage having step-by-step movements and jump movements, state-controlling means for determining the character of drive of said computing wheels by said actuating mechanism under the control of said numeral keys, a stop or lug determining the jump movements of said carriage and the action of said state-controlling means, and shifting means for effecting a clearance between said stop or lug and said state-controlling means during a change in the computing zone.

30. The combination with a carriage and a column stop therefor, of tabulator stops for controlling the carriage through the medium of said column stop, computing mechanism, a state-controlling mechanism for the computing mechanism controlled by said column stop, and means controlled by a tabulator stop for silencing the state-control mechanism during a traverse of the carriage under control of said tabulator stop.

31. The combination with computing mechanism, of a traveling carriage, column stops on the carriage, a state-controlling mechanism coöperating with the column stops to determine the state of the computing mechanism in different computing zones as determined by the carriage, tabulator stops controlling the carriage through the medium of the column stops, and means under control of a tabulator stop for rendering the state-control ineffective by any column stop during a traverse of the carriage under control of said tabulator stop.
